(57) **CLAIM**

The ornamental design for a telescope adapter for smartphone, as shown and described.

DESCRIPTION

FIG. 1 is a top, front, right-side perspective view of a telescope adapter for smartphone showing my new design; FIG. 2 is a top, rear, left-side perspective view thereof; FIG. 3 is a bottom, rear, left-side perspective view thereof; FIG. 4 is a front elevational view thereof; FIG. 5 is a rear elevational view thereof; FIG. 6 is a left-side elevational view thereof; FIG. 7 is a right-side elevational view thereof; FIG. 8 is a top plan view thereof; FIG. 9 is a bottom plan view thereof; FIG. 10 is a perspective view of FIG. 1, with two parts moved along the direction of the arrows; and, FIG. 11 is a perspective view of FIG. 10, with a portion rotated about a center axis of the disc component. The broken lines shown in the drawings represent portions of the telescope adapter for smartphone that form no part of the claimed design.
